CIGARETTE ASH TRAY

Cecil Monroe Trimble, Waukesha, Wis.

Application January 16, 1941, Serial No. 374,754

2 Claims. (Cl. 131—240)

This invention aims to provide a simple structure whereby a burning cigarette, mounted in a seat on an ash tray, with the burning end of the cigarette disposed inwardly and above the tray, will first tilt downwardly at its outer or unlighted end, as the cigarette burns, to raise the burning portion of the cigarette out of the seat, the cigarette being caused to roll laterally, and finally to slide lengthwise and inwardly, to dispose the burning end of the cigarette within the tray. As the result of such an operation, and the structure from which the operation flows, it is impossible for the cigarette to tilt downwardly at its unlighted or outer end, and fall out of the tray, with damage to furniture and with possible conflagration.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in top plan, a device constructed in accordance with the invention;

Fig. 2 is a transverse section on the line 2—2 of Fig. 1;

Fig. 3 is a fragmental top plan, showing a modification;

Fig. 4 is a section on the line 4—4 of Fig. 3;

Fig. 5 is a section on the line 5—5 of Fig. 3;

Fig. 6 is a top plan, showing another modification;

Fig. 7 is a top plan showing a further modification;

Fig. 8 is a section on the line 8—8 of Fig. 7;

Fig. 9 is a section on the line 9—9 of Fig. 7;

Fig. 10 is a section on the line 10—10 of Fig. 7;

Fig. 11 is a top plan showing another modification;

Fig. 12 is a section on the line 12—12 of Fig. 11;

Figs. 13, 14 and 15 are diagrammatic views illustrating the operation of the device forming the subject matter of this application.

Referring to Figs. 1, 2, 13, 14 and 15, and disregarding duplication, and such adjuncts as the match case holder 1 of Figs. 1 and 2, there is

shown an ash tray 2, comprising a bottom 3 and an upstanding rim 4, defining a bowl 5.

The rim 4 has an inwardly and downwardly slanting surface 6, leading to the bowl 5. On the slanting surface 6 of the rim 4, there is an upstanding lug 7. The lug 7 is provided with a transversely concaved cigarette seat 8, leading to the bowl 5, the bottom of the seat having a downward and inward slope.

The upper edges 9 of the seat 8 converge as they extend outwardly, to form a point or inner fulcrum 10. The inner fulcrum 10 is spaced inwardly from the outer edge of the slanting surface 6, and the outer edge of the slanting surface forms an outer fulcrum 11. The side surfaces 12 of the lug 7 converge outwardly, to a downwardly and outwardly inclined edge 14, and they diverge downwardly and laterally.

Referring to Fig. 13, a cigarette 15 is shown in the seat 8 of the lug 7. As the inner portion of the cigarette 15 burns away, the outer portion of the cigarette becomes heavier than the inner portion. The cigarette then tilts vertically, with the point 10 as a fulcrum, and assumes the horizontal position shown at 16 in Fig. 13.

As the cigarette continues to burn away, its outer, heavier end swings downwardly, until the cigarette assumes the tilted position shown at 17 in Fig. 13, the cigarette then being supported by the inner fulcrum 10 and by the outer fulcrum 11. Owing to the slant edge afforded at 14, the cigarette can tilt from the position shown at 16 to the position shown at 17, to find support on the inner fulcrum 10 and on the outer fulcrum 11. As the cigarette tilts from the position 15 to the position 16, it is raised clear of the seat 8, and can roll laterally, either to one side or the other.

The inner portion of the cigarette is carried laterally, as shown at 18 in Figs. 14 and 15, with the outer fulcrum 11 as a pivot. The lateral movement of the cigarette is brought about by the converging edges 9 of the seat 8, and by the laterally and downwardly diverging surfaces 12 of the lug 7. These elements 9 and 12, acting singly or together, bring about the result under discussion. Up to this point, the cigarette may be regarded as being in the position shown at 18, in Figs. 14 and 15. The slanting surfaces 12 of the lug 7 then carry the butt of the cigarette laterally, until the cigarette rests on the sloping surface 6, as shown at 19 in Figs. 14 and 15.

The movement of the cigarette from the position shown at 15 in Fig. 13 to the position shown at 19 in Fig. 15, has been traced through, step

by step, in the interest of clarity, and to point out the functions of various parts. Generally stated, however, the movement of the cigarette from the position shown at 15 in Fig. 13 to the position shown at 19 in Fig. 15, is a more or less compound movement.

The structure and the steps of operation are such that as a cigarette burns away at its inner end, the cigarette ultimately will move inwardly, into the tray, instead of sliding outwardly, into a position in which the burning end of the cigarette will make contact with a table or the like, the results incident to such an operation being common and well known.

Passing to the form shown in Figs. 3, 4 and 5, parts hereinbefore described have been designated by numerals already used, with the suffix *a*. The outer end of the lug 7a is blunted, as shown at 20. On the downwardly concaved surface of the seat 8a there is a longitudinal, up-standing rib 21, having oppositely slanting side surfaces. The rib 21 aids in imparting a lateral movement to the cigarette, especially if the cigarette is flattened, or is not of cylindrical cross section.

In Fig. 6, parts hereinbefore described have been designated by numerals already used, with the suffix *b*. The form shown in Fig. 6 resembles the form shown in Fig. 3 closely, aside from the fact that the rib 21 of Figs. 3, 4 and 5 is omitted.

In Figs. 7, 8, 9 and 10, parts hereinbefore described have been designated by numerals already used, with the suffix *c*.

In the form shown in Figs. 7 to 10, the lug 7c is not tapered outwardly, and the edge 14c of the lug does not have a downward and outward slope.

In the form depicted in Figs. 11 and 12, parts hereinbefore described have been designated by numerals already used, with the suffix *d*.

In Figs. 11 and 12, the side surfaces 12d of the lug 7d are composed, each, of plane, angularly disposed parts, the inclined edge 14 of Fig. 3 being replaced by a triangular, correspondingly slanted, plane surface 14d.

In any of its forms, the device forming the subject matter of this application will be found

efficient to consummate the objects set forth in the opening portion of this specification, and in succeeding parts thereof.

The word "cigarette," employed hereinbefore and hereinafter, is to be construed to mean any smoker's article wherewith the device is adapted to be used, and imposes no limitation.

What is claimed is:

1. In a smoker's convenience, a body including a support provided with a cigarette seat, the lateral edges of which converge outwardly, to form a cigarette fulcrum, the support being provided on its opposite sides with downwardly and laterally sloping cigarette-deflecting surfaces leading from the seat, the support being provided with a rib extended lengthwise of the seat and constituting means for directing a cigarette laterally toward the cigarette deflecting surfaces.

2. In a smoker's convenience, a tray including a rim provided with an upper, downwardly and inwardly slanting surface, the portion of the rim which is at the outer end of said surface constituting an outer fulcrum, there being a lug on said surface, the outer end of the lug being disposed close to the outer fulcrum but spaced inwardly a slight distance therefrom, the lug being of less width than said surface and being provided on its upper surface with a cigarette seat which slants upwardly and outwardly, the lateral, upper edges of the seat converging outwardly to define an apex constituting an inner fulcrum on which a cigarette, as the inner end thereof burns away, may tilt until downward movement of the outer portion of the cigarette is stopped by engagement with the outer fulcrum, the inner fulcrum being elevated sufficiently with respect to the outer fulcrum so that the inner portion of the cigarette then will be clear of the seat, the lug having oppositely-disposed, outwardly-converging side surfaces extending at least to the apex and having a downwardly-diverging slant, the side surfaces constituting means for deflecting a cigarette laterally upon the downwardly and inwardly slanting surface of the rim, while the cigarette

is engaged with the outer fulcrum.
